UNITED STATES PATENT OFFICE.

JOSEPH SHAW GAUNT, OF MANCHESTER, AND HARRY DYSON, OF HUDDERSFIELD,
ENGLAND.

FLIER-FRAME FOR SPINNING, DOUBLING, AND THE LIKE.

1,103,194.

Specification of Letters Patent.

Patented July 14, 1914.

Application filed July 10, 1911. Serial No. 637,603.

To all whom it may concern:

Be it known that we, JOSEPH SHAW GAUNT, of Cromford Court, Market street, Manchester, and HARRY DYSON, of 67 May street, Lockwood, Huddersfield, both in England, have invented certain new and useful Improvements in Flier-Frames for Spinning, Doubling, and the like, of which the following is a specification.

10. This invention relates to an improved flier frame for use in the continuous spinning, doubling, and the like of cotton, worsted, silk, and other fibrous materials the chief object being to provide improved bearings 15 for the spindle, another object being to provide the flier with an easily replaceable member that comprises or includes means for engaging with the thread.

The accompanying drawing shows, in vertical section, one construction of flier, spindle, and bearings according to this invention.

A is the spindle, B the bolster, C a stationary bolster rail, D a vertically movable spindle rail, and E the flier. The upper portion of the flier E is in the form of a cylindrical cup and provided with a detachable member e provided or formed with means for engaging with the thread: the 30 said detachable member e consists of a lateral flange e² having slits or eyes for engaging with the thread and a vertical flange e' that is tapped internally so as to screw upon the screw-threaded portion E⁴ of the 35 upper portion of the cup-shaped flier E. This construction enables a new member e to be quickly substituted for an old member that has become worn by contact with the thread, and this without renewing the 40 entire flier.

The flier E is formed with a wherve f and its lower portion extends outwardly at f' and downwardly at f². The flier E is mounted upon ball bearings comprising inner and 45 outer ball rings b b': the inner ring b is mounted upon a shoulder B' formed upon the upper portion of the bolster B, the said inner ring being held upon the said shoulder by a nut b^x; the outer ring b' is mounted 50 ed upon the inner face of the downwardly extending portion f² of the flier and wherve f. The bolster tube B is mounted in the fixed rail C and is provided with an annular lateral extension B² having an upwardly extending flange B³; these portions 55

B² and B³ coöperate with the inner portion of the bolster tube to form an annular groove or receptacle B^x adapted to contain a lubricating device for the ball bearing situated immediately above, and the flange f² of the wherve extends downwardly a sufficient distance to over-lap the flange B³ thus closing the lubricating chamber and preventing dust and fly from clogging the bearing and lubricating receptacle. The two 65 flanges f² and B³ are each formed with an opening c; when the apparatus is not working the openings c may be brought into coincidence to enable the lubricant in the receptacle B^x to be renewed. The lubricating 70 device may consist of a tubular cotton wick impregnated with oil which is conveyed to the ball bearing by capillary attraction.

A footstep bolster d is mounted in the vertically movable spindle rail D and a 75 loose fitting oil-cup d' is arranged therein and is supported by a wire cradle d³ having its upper ends d⁴ turned inward to engage with holes d⁵ in the bolster d into which they are sprung, the cradle being retained in position by means of grooves d⁶. The spindle foot A' rests on a hardened steel disk d⁷ and is retained there by a guiding cover d⁸. The loose-fitting oil cup d' is according to this invention formed with 80 an annular projection or swell d^x at its upper portion; this allows the lower end of the spindle a certain amount of play or lateral movement.

Having described our invention what we 90 claim and desire to secure by Letters Patent is:—

1. The combination with a spindle of a bolster provided with a tubular extension and an annular lateral extension provided 95 with an upwardly extended flange, said flange being in spaced relation to the tubular extension, said flange and tubular extension coöperating to form a lubricating channel, a flier provided with a depending 100 sleeve inclosing said flange to shield the channel, said tubular extension being provided with an annular shoulder that is in the same plane as the upper edge of the flange, a bearing member resting on said shoulder, and a complementary bearing member carried by said sleeve.

2. The combination with a spindle, of a bolster provided with an integral tubular and an integral annular lateral extension, 110

the lateral extension being provided with an upstanding flange that surrounds the tubular extension in spaced relation, the tubular extension and the flange forming between them a lubricant channel, the tubular extension being provided with an intermediate bearing seat in the same plane as the upper edge of the flange, a flier frame provided with means for inclosing said flange

to seal the channel and complemental bearing rings carried by said tubular extension and said flier frame in a plane above said flange. 10

J. SHAW GAUNT.
